The side opposite to that shown in FIG. 4 is a mirror image thereof. The sides and rear, with the exception of increased width, of the embodiment of FIG. 6 are the same as shown in FIGS. 4 and 5, respectively.

The dominant features of my design reside in the portions shown in full lines.

I claim:

The ornamental design for a laundry tub, as shown and described.
